Primary Examiner — Khawaja Anwar*Assistant Examiner* — Mojtabe Tehrani(74) *Attorney, Agent, or Firm* — Hinshaw & Culbertson LLP(57) **CLAIM**

The ornamental designs for an infant safety flotation device, as shown and described.

DESCRIPTION

FIG. 1 is a perspective view of the first embodiment of an infant safety flotation device, showing my new design; FIG. 2 is a right side view thereof;

FIG. 3 is a left side view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective view of the second embodiment of an infant safety flotation device, showing my new design;

FIG. 9 is a right side view thereof;

FIG. 10 is a left side view thereof;

FIG. 11 is a front elevation view thereof;

FIG. 12 is a rear elevation view thereof;

FIG. 13 is a top plan view thereof; and,

FIG. 14 is a bottom plan view thereof.

The broken lines around the FIGS. show portions of the infant safety flotation device, which form no part of the claimed design. The bold broken interior lines show shading. The broken lines within the FIGS. show portions of the infant safety flotation device, which form no part of the claimed design.

1 Claim, 8 Drawing Sheets(56)
